US00D964324S

(12) **United States Design Patent** (10) Patent No.: **US D964,324 S**
Boyd et al. (45) Date of Patent: ** Sep. 20, 2022

(54) **EARPHONE**(71) Applicant: **Apple Inc.**, Cupertino, CA (US)(72) Inventors: **Robert Boyd**, Los Angeles, CA (US); **Sean Stewart Corbin**, South Lake Tahoe, CA (US); **Duy P. Le**, Los Angeles, CA (US); **Guillaume Raoult**, San Francisco, CA (US); **Christopher Kuh**, San Francisco, CA (US); **Robert Brunner**, Glen Ellen, CA (US)(73) Assignee: **Apple Inc.**, Cupertino, CA (US)(***) Term: **15 Years**(21) Appl. No.: **29/825,907**(22) Filed: **Feb. 7, 2022****Related U.S. Application Data**

(63) Continuation of application No. 29/776,667, filed on Mar. 31, 2021, now Pat. No. Des. 942,971, which is a continuation of application No. 29/721,504, filed on Jan. 21, 2020, now Pat. No. Des. 916,057, and a continuation of application No. 29/721,503, filed on Jan. 21, 2020, now Pat. No. Des. 916,056, which is a continuation of application No. 29/685,002, filed on Mar. 25, 2019, now Pat. No. Des. 897,320, and a continuation of application No. 29/685,002, filed on Mar. 25, 2019, now Pat. No. Des. 897,320.

Primary Examiner — Paula Allen Greene*(74) Attorney, Agent, or Firm* — Sterne, Kessler, Goldstein & Fox P.L.L.C.(57) **CLAIM**

The ornamental design for an earphone, as shown and described.

DESCRIPTION

FIG. 1 is a front perspective view of an earphone showing the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the earphone that form no part of the claimed design.
